COMBINATION AIR CONDITIONER AND
REFRIGERATOR

Pietro Maniscalco, Toledo, Ohio

Application May 18, 1940, Serial No. 335,983

19 Claims. (Cl. 62—134)

This invention relates to improvements in a combination air conditioner and refrigerator.

One of the main objects of this invention is to provide a domestic type of refrigerator combined with air conditioning means, to be especially suited for use in the kitchen, and likewise for use in other rooms in the home and in apartments, and the like; whereby the customary refrigeration for food and drink is provided, and the air may also be cooled and conditioned whenever desired.

Another object of this invention is to provide a domestic type of refrigerator equipped with an air conditioner which is adapted to cool the air, and which is furthermore adapted and is selectively operable to either remove the moisture of condensation from the air and dehydrate the air, when it is excessively moist; or else to restore such moisture to the air while circulating thru the conditioner; or, on the other hand, to add moisture to the air, whenever it is too dry.

Another object of this invention is to provide an improved construction comprising a refrigerator having an air conditioner combined therewith which can be operated in conjunction with the refrigerator whenever the room temperature is warm; and can also be readily shut-off to utilize the refrigerator alone, when the temperature is moderate; and which can furthermore be utilized for conditioning the air, while the refrigerator is retained idle.

Another object of this invention is to provide a combination refrigerator and air conditioner which is arranged to freeze a quantity of water around the air passage and utilize it in cooling the air, and thereby provide a hold-over or excess of stored cooling medium, adapted to be utilized more particularly during the warmer period of the day.

These and various other objects and advantages are attained with this invention, as will become apparent from the following description, taken in connection with the accompanying drawings wherein the invention is illustrated in its preferred form, it being apparent that various other arrangements and forms of construction may be adopted for carrying out the objects and purposes of this invention.

In the drawings:

Fig. 1 is a front elevational view of a combination air conditioner and refrigerator having my invention applied thereto.

Fig. 2 is a side elevational view thereof, with parts broken away.

Fig. 3 is a side elevational view of the lower

part of the cabinet, taken along line 3—3 of Fig. 1, showing the improved heat exhausting means on the machinery chamber.

Fig. 4 is a plan view of the air deflecting means, which is removably and adjustably mounted on the cabinet.

Fig. 5 is an enlarged vertical sectional view of the invention, taken on line 5—5 of Fig. 2.

Fig. 6 is a horizontal sectional view, taken on line 6—6 of Fig. 5, the thermostat being omitted therefrom.

Fig. 7 is an enlarged partial sectional view, taken on line 7—7 of Fig. 1, illustrating the water freezing means and the air forcing means.

Fig. 8 is a diagrammatic view illustrating a refrigerating unit adapted for use with this invention.

Fig. 9 is a partial sectional view, being similar to Fig. 7, but indicating the several water containing means arranged for adding moisture to the air passing thru the conditioner.

Fig. 10 is an enlarged sectional view of the spraying means, taken on line 10—10 of Fig. 9.

Fig. 11 is a diagrammatic view illustrating suitable electric means, including electric motors and control switch means, adapted for use with this invention.

The drawings illustrate this invention in its preferred form of construction, comprising a cabinet 10 which contains an air conditioning part or conditioner 11 and a refrigerating part or refrigerator 12 including a storage chamber for food and drink. Said cabinet is provided with insulated walls, including a rear wall 13, side walls 14 and 15, a top 16, a lower partitioning wall 17, and a front wall 18 containing an insulated door 19 therein providing access to the refrigerator chamber 12. The lower part 15' of side wall 15, which extends along the intake part of conditioner 11, need not be insulated.

A bottom wall 20 is spaced below wall 17, providing a machinery chamber 21 therebetween which houses the refrigerating unit 22, while supporting legs 23 space said bottom wall 20 above the floor. Said chamber 21 includes a removable front plate 24, thus providing access to the machinery in said chamber, and includes inlet louvres 25 at one side, and an exhaust opening 26 at the opposite side which is provided with a louvre-equipped closure plate 27 slidable in flange means 28 for closing said opening 26, when the air conditioner is not in use.

Heat exhausting means is furthermore provided on the machinery chamber 21 and includes

a panel 29 slidable in said flange means 28 and having an exhaust conduit 31 extending therefrom, which has a mounting shield or plate 32 at its outer end adapted to be mountable in a window frame. Said shield has a part 32' extendible thereon, by the use of means 33, as indicated in Fig. 1, to be suited for windows of various widths.

The refrigerating unit 22 in compartment 21 may be of a standard type, being shown herein as comprising a compressor 35, a driving motor 36, a condenser 37, a tank 38, and the refrigerant conduits connecting the same, including a feed conduit 39 extending from tank 38 and equipped with an expansion valve 41, and also a return conduit 42 for returning the refrigerant to the compressor 35. A fan 44 is driven by the motor 36, for moving the air thru the inlet openings 25 and over the condenser and other members, and from chamber 21 out thru the outlet opening 26, to cool the heated members of the refrigerating unit.

The refrigerating part or storage chamber 12 is provided with an insulated partitioning wall 46 placed intermediate the two side walls 14 and 15, and continuing with a curved upper portion 47, thus providing an air channel in the space between wall parts 15 and 15', and 46 and 47. An insulated partitioning wall 48 extends from part 47 across the upper part of the cabinet and provides the top of the storage chamber, while a cooling unit including coils 49 is positioned in the storage chamber 12, these coils being connected with conduits 39 and 42 of the refrigerating unit, as indicated in Fig. 8.

The air conditioning mechanism 11 comprises an air conducting channel extending thru the cabinet 10 and including a primary cooling chamber 51 at the lower part of the cabinet, and a secondary or main cooling chamber 52 at the upper part of the cabinet, air forcing means 53 being interposed between said chambers and preferably consisting of a blower fan having its housing 53' seated upon the curved wall portion 47, substantially as indicated in the drawings. A small motor 54 for driving said fan is also supported on said curved portion 47, said fan forcing the air from chamber 51 upwardly thru chamber 52. A door 55 in rear wall 13 provides access to motor 54.

An annular water receptacle or drip trough 56 is supported on wall 48; and a water jacket 57 is supported by lugs 58 on said trough to provide a space 58' between said trough and jacket, as indicated in Fig. 5, for the air to circulate there thru and around said jacket. Said jacket includes spaced and substantially annular walls 59 and 59' providing a chamber 57' adapted to contain water therein, while a detachable cover 60 is placed on said jacket when the air is moist, and is removable therefrom to expose the water in chamber 57' to the air, when it is desired to add moisture to the circulating air, as indicated in Fig. 9.

Primary cooling means or coils 61 are provided in chamber 51 and are connected by a conduit 62 with the return conduit 42 of the refrigerating unit 22, while a shut-off valve 63 is interposed between said coils and said conduit, to be closed when the cooling coils 49 of the refrigerator alone are actuated, without utilizing the air cooling means.

A main freezing unit 64 is placed in thermal relation with the water jacket, and it preferably includes coils 65 positioned in the water in the

jacket chamber 57', and also coils 66 placed adjacent and inward of the jacket wall 59. Said coils are connected together and the coils 65 are connected by a conduit 67 with primary coils 61, while coils 66 are connected by a conduit 68 with conduit 39 of the refrigerating unit. A shut-off valve 69 is interposed in conduit 68, adapted to shut off the freezing unit when the air conditioner is not in use.

10 An inlet opening 71 is provided at the lower end of chamber 51, and has doors or slidable panels 72 mounted therein by guide means 73, so that said inlet opening can be opened to the size desired and can be closed entirely when the conditioner is not in use.

15 The outlet opening 74 in the top 16 of the cabinet is provided with deflecting means 75 which is removable from opening 74 and can be turned and placed therein and its vanes 76 can be suitably tilted, so as to deflect the air in the particular direction and at the particular slant desired, as well as to direct it vertically up from the outlet opening. A cover 77 is provided, and can be readily substituted for deflecting member 75, when the conditioning means is not in use.

20 An air spreading member 81, which is substantially bowl-shaped, is mounted with bracket means 82 on partition wall 48, so that member 81 is centered in the lower part of the channel 30 extending thru the jacket 57, substantially as indicated in the drawings. The air driven upward by fan 53 will thus be spread outwardly and forced closely along coils 66 and the inner wall 59 of the water jacket, to properly utilize the cooling effect of the freezing unit, while the cool air around the outside of the jacket will be drawn thru space 58' by suction and carried along up with the air forced upward around spreader 81.

25 A drain pipe 83 is depended from trough 56 to drain the water therefrom down to a drip pan 84 at the lower end of chamber 51, and therefrom thru a discharge pipe 85 to a receptacle 86, as indicated in the drawings, or to any suitable drain means. A shut-off valve 87 with a handle 87' is provided on pipe 83, and a shut-off valve 88 with a handle 88' is provided on a pipe 85, for closing said pipes and retaining the moisture respectively in trough 56 and likewise in pan 84, when it is desired to add moisture to the air circulating thru the conditioner. A plug 89 closes an aperture in the bottom of trough 56, and a rod 90 arising therefrom can be manipulated to release said plug for draining trough 56.

30 Sprinkling means 91 is also provided and includes a tubular nozzle with openings, being supported by a conduit 92 which depends from trough 56, into the upper part of chamber 51, so as to sprinkle the water from said trough into the air ascending thru the air channel. A valve 60 93 with a handle 93' is also provided on conduit 92, so as to close the valve whenever the sprinkler is not to be used.

35 Control means is also provided to enable operating the two motors 36 and 54 together, when the air conditioner as well as the refrigerator are to be used together; and likewise to operate either motor alone while the other is retained idle. For this purpose, as indicated in Fig. 11, the motor 36 of the refrigerator unit has a control switch 96 interposed in one of its conductor wires 97 and 97' which are connected electrically with the current inlet socket 98 on the cabinet; while the motor 54 of fan 53 has a control switch 99 interposed in its conductor wires 100 and 100' which are connected with said wires 97 and 97'.

A thermostat 101 may also be provided having a tube 102 extending therefrom to a thermal element 103 which is placed adjacent the freezing unit 64, being shown in Fig. 9 as mounted on coils 66. A finger 104 on the thermostat actuates a switch 105 which is interposed in wire 97', so as to break the circuit of motor 36, whenever the temperature of the freezing coils and of the water in the jacket chamber 57' has descended below the desired degree.

With this combination arrangement and construction the driving motor 36 can be retained idle, and motor 54 alone operated to drive fan 53; thus adapting this device for merely humidifying the air when it is dry and the weather is sufficiently cool, while the refrigerator and the air cooling means with its motor 36 are retained idle. The jacket 57 is then filled with water and left uncovered, and the air spreader 81 is also filled with water, as shown in Fig. 9, and the pan 84 is then likewise filled with water with the valve 88 closed; thereby causing the air which is being forced by the fan thru the conditioning chambers 51 and 52 to absorb moisture from the water contained in jacket 57, spreader 81, and pan 84.

For dehydrating the air, when it contains an excessive amount of moisture, the cover 60 is retained on jacket 57 and valve 93 on sprinkling means 91 is closed, while valves 87 and 88 on the drain pipes 83 and 85 are opened, thus enabling the moisture of condensation from jacket 57 and coils 66, which has dripped into trough 56, to be drained from the trough thru said drain pipes into suitable drain means.

When the air is normal or not too moist, then the sprinkling means 91 is preferably utilized, by opening its valve 93, and closing the valve 87 on drain pipe 83, thus causing the moisture of condensation from the jacket and coils to be sprinkled into the air ascending thru chamber 51; thereby returning the moisture of condensation to the circulating air and also aiding in settling dust particles and impurities that are present in the air.

When the air is too dry, then drain valve 87 in drain pipe 83 is closed, while valve 93 on sprinkler 91 is opened, and the cover 60 from the jacket 57 is removed, and at the same time valve 88 in drain pipe 85 is closed, to retain water in pan 84, and water may also be placed in the bowl-shaped air spreader 81. The moisture of condensation is thereby returned thru trough 56 and sprinkler 91 to the circulating air; and at the same time the water in the open jacket chamber 57', and in the pan 84, and optionally in the air spreader 81, will thru evaporation add moisture to the circulating air, thereby effectively moistening the dry air.

Both of the motors 36 and 54 will be operated in utilizing the device for cooling and conditioning the air.

It is apparent from the above disclosure that this invention presents a true combination construction of air conditioner and refrigerator to be used in conjunction, and which can also be used for either purpose alone; and that it is adapted to be utilized for cooling the air, and also for removing moisture from the air when it is too wet, or for adding moisture to the air when it is too dry.

I claim:

1. In a domestic type of refrigerator including a cabinet provided with a storage chamber and a refrigerating unit, air conditioning means com-

prising an air channel extending thru the cabinet adjacent the storage chamber and including air inlet and outlet means thereon, a jacket having spaced walls providing an annular water chamber interposed in said channel and forming part thereof, a freezing unit associated with said jacket and operable by said refrigerating unit adapted to freeze water in the jacket chamber and cool the air flowing thru the channel and jacket, and 10 valve controlled sprinkling means and draining means associated with the jacket to receive moisture condensed on the latter, whereby to either restore moisture of condensation to the air circulating thru the channel, or to remove said moisture for dehydrating the air.

2. In a domestic type of refrigerator including a cabinet provided with a refrigerating unit and with an insulated storage chamber adapted to be cooled by said unit, air conditioning and conducting means within the cabinet and including air inlet and outlet means, a jacket providing an annular water chamber interposed in said air conducting means and forming part thereof, a freezing unit in thermal relation with said jacket and operable by said refrigerating unit adapted to freeze water in the jacket, a water receptacle below the jacket adapted to receive moisture condensed on the latter, means to force the air thru the conducting means, and sprinkling means connected with said receptacle to distribute the moisture of condensation into the air circulating thru the conducting means.

3. The subject matter set forth in claim 2, wherein the sprinkling means is provided with a 35 shut-off valve, and a valve controlled drain means is provided for the receptacle, whereby to either return the moisture of condensation to the circulating air or else to remove such moisture for dehydrating the air.

4. In a domestic type of refrigerator including a cabinet containing a machinery chamber having a refrigerating unit therein and a storage chamber insulated therefrom, air conditioning means comprising an air channel extending thru the cabinet and including inlet and outlet means thereon, means to conduct heated air from the machinery chamber out of the room which is being conditioned, an annular water container interposed in said channel and its central part forming a part thereof, a freezing unit in thermal relation with said container and operable by the refrigerating unit to freeze water in the container, means to force the air thru the channel, a receptacle below the container to receive moisture condensed on the walls of the latter, sprinkling means connected with said receptacle to distribute the moisture of condensation into the air in said channel, and a receptacle with valve-equipped drain means in the lower part of said channel, adjacent the air inlet means, adapted to receive and either to retain the sprinkled water therein or to drain it therefrom.

5. In a domestic type of refrigerator including a cabinet containing a storage chamber and a machinery chamber having a refrigerating unit therein, an air conditioner comprising an air channel extending thru the cabinet adjacent the storage chamber and including lower inlet means and upper outlet means, a jacket with spaced walls providing an annular water chamber having an openable top and its central part forming part of said channel, a freezing unit in thermal relation with said jacket and operable by the refrigerating unit, means to force the air upward thru the channel and jacket, a trough be-

low the jacket to receive moisture of condensation therefrom, a dished air spreader at the lower part of the jacket to spread the air against the inner wall thereof, and sprinkling means depending from the trough to distribute moisture in the air ascending in the channel, whereby said air spreader is adapted to contain water, and it with the open jacket and the sprinkler are adapted to humidify the circulating air.

6. The subject matter set forth in claim 5, wherein the trough is spaced below the jacket, adapting the cool air from around the outside of the jacket to be drawn thru said space and forced along upward with the air flowing thru the jacket.

7. In a domestic type of refrigerator including a cabinet having a lower chamber containing a refrigerating unit and an insulated storage chamber above the same, air conditioning means in the cabinet comprising an air inlet at the lower part of the cabinet and an air channel arising therefrom along the storage chamber having air outlet means with deflecting means at its upper end, heat exhausting means to discharge heated air from said lower chamber to a point remote therefrom, trough means at the upper part of said air channel and provided with means to spray moisture into the ascending air, an annular water jacket above said trough means and spaced above the same to provide an air circulating space therebetween, the central part of the jacket providing the upper part of the air channel, and means below said trough and protected thereby from moisture of the jacket, adapted to force the air thru said channel and outlet means.

8. The subject matter set forth in claim 7, wherein the spraying means are depended from the lower end of the trough into the air channel, the top of the water jacket is adapted to be held open, and moisture containing means with valve-controlled drain means is provided at the bottom of said channel adjacent the inlet means, whereby to humidify the air.

9. In a domestic type of refrigerator including a cabinet provided with a chamber having a refrigerating unit therein, exhaust means to discharge heated air from said chamber and unit, an air channel extending thru the cabinet and provided with a lower inlet and an upper outlet, an annular water jacket at the upper end of said air channel and forming a part thereof, a water receptacle below the jacket to receive moisture of condensation from the same, a freezing unit in thermal relation with said jacket and actuated by said refrigerating unit, fan means below said water container and protected thereby from moisture of the jacket, adapted to force the air up thru said channel and outlet means, means placed centrally in the lower part of the jacket to spread the air toward the inner wall thereof, and means depending from the receptacle to convey moisture therefrom.

10. The subject matter set forth in claim 9, wherein the top of the water jacket is adapted to be held open, and the air spreading means is dish-shaped adapted to contain water therein, adapting the device for humidifying the circulating air.

11. The subject matter set forth in claim 9, wherein said depending means includes means to sprinkle moisture into the air channel, the top of the water jacket is adapted to be held open, the air spreading means is adapted to contain

water therein, and moisture receiving means with valve-controlled means is provided at the bottom of the channel adjacent the inlet means, adapting the device for humidifying air passing thru the channel.

12. In a domestic type of refrigerator including a cabinet containing a machinery chamber with a refrigerating unit therein and a storage chamber insulated therefrom, an air conditioner in said cabinet comprising an air channel including an inlet part with air inlet means and an outlet part with air outlet means thereon, a jacket with spaced walls providing an annular water chamber mounted in said outlet part and forming part of said channel, a freezing unit in thermal relation with said jacket and a primary cooling coil in said inlet part and connected with said unit, both being actuated by said refrigerating unit, means to receive moisture of condensation from said jacket and to distribute it in the air in said channel, and means to force the air thru said channel for conditioning the same.

13. In a domestic type of refrigerator including a cabinet containing a machinery chamber with a refrigerating unit therein and a storage chamber insulated therefrom, an air conditioner in said cabinet comprising an air channel including an inlet chamber with air inlet means extending along said storage chamber and an outlet chamber having air outlet means with air deflecting means thereon, means to conduct heated air from said machinery chamber to a point remote therefrom, a jacket with spaced walls providing an annular water chamber mounted in said outlet chamber and forming part of said air channel, a blower fan mounted between said two chambers to force the air thru said channel, a trough spaced below said jacket to receive condensed moisture from the latter and protect the fan from said moisture, a freezing unit in thermal relation with said jacket and a primary cooling coil in said inlet chamber, both being actuated by said refrigerating unit, and means connected with said trough to sprinkle moisture into the air in said channel.

14. In a domestic type of refrigerator including a cabinet containing a machinery chamber with a refrigerating unit therein and a storage chamber insulated therefrom, an air conditioner in said cabinet comprising an air channel including an inlet chamber with inlet means at the lower end and an outlet chamber with outlet means at the upper end, a jacket with spaced walls providing an annular water chamber positioned adjacent said outlet means and forming part of the channel, sets of coils actuated by the refrigerating unit and including a primary coil in the inlet chamber and a pair of freezing coils, one placed in the water between the walls of the jacket and the other placed in the air channel adjacent the inner jacket wall, means to receive moisture of condensation from said jacket and to conduct the same away therefrom, and means to force air thru said channel.

15. The subject matter set forth in claim 14, wherein the moisture conducting means includes valve-controlled drain means and also valve-controlled sprinkling means, either one being selectively usable to serve either in dehydrating the air or in moistening the air.

16. The subject matter set forth in claim 14, wherein the moisture conducting means is provided with sprinkling means in the air channel, dished means is provided in the jacket to spread the air against its inner wall and the coils inward

thereof, said dished means is adapted to contain water, and the top of the water jacket is adapted to be retained open, whereby to humidify the circulating air.

17. A device of the character described comprising a cabinet containing a machinery chamber with a refrigerating unit therein, air conditioning means in said cabinet containing an air channel extending therethru and including an inlet part with air inlet means at one end and air outlet means with adjustable deflecting means at the other end, a jacket with spaced walls providing an annular water chamber with an openable top mounted near said outlet means and its central part forming part of said channel, cooling means including a main cooling unit associated with said jacket and primary cooling coils mounted in said inlet part and connected with said cooling unit, both being actuated by said refrigerating unit, means to force the air thru said channel, means to spread the air against the inner wall of the jacket, means to receive moisture of condensation from said jacket and said cooling unit, means on the receptacle means to distribute said moisture into the air in said channel, drain means on said receptacle means, and control-valve means adapted to shut off either said distributing means or said drain means while the other remains operative.

18. A combination air conditioner and refrigerator comprising a cabinet containing a refrigerating unit with a driving motor, an insulated storage chamber containing a cooling unit actuated by said refrigerating unit, an air channel extending thru the cabinet and including lower inlet means and upper outlet means, an annular water jacket interposed in the channel near the outlet means, a chilling unit associated with the jacket and operable by the refrigerating unit, control means for shutting-off the chilling unit, a moisture receptacle beneath the jacket and being provided with valve-controlled drain means

and also with valve-controlled sprinkling means extending into said channel, adapted to selectively utilize either the drain means or the sprinkling means to either dehydrate the circulating air or to rehumidify the same, air forcing means in the channel and a driving member therefor, and control means for retaining either said driving member or said driving motor inactive while the other is active, adapting the device to be utilized only as a refrigerator or likewise only as an air circulating mechanism, or both in combination.

19. A combination air conditioner and refrigerator comprising a cabinet containing a machinery chamber at its lower end having a refrigerating unit therein, means to conduct heated air from said chamber, an insulated storage chamber in said cabinet containing a cooling unit actuated by said refrigerating unit, an air channel extending thru the cabinet and including lower inlet means and also upper outlet means provided with readily adjustable and removable deflecting means thereon, an annular water jacket interposed in said channel and its central part providing an air passage adjacent the outlet means, a freezing unit including coils positioned in the water in said jacket and also coils positioned in said air passage, said unit being operable by the refrigerating unit, means for forcing air thru the channel, deflecting means interposed in the channel above said forcing means to direct air toward the inner wall of said jacket, a moisture receptacle beneath the jacket and provided with sprinkling means adapted to moisten the circulating air, a drain pipe depending from said receptacle, control valve means for said sprinkling means and also for said pipe, to selectively shut-off either one thereof and utilize the other, and control means for said freezing unit, whereby to render it either inoperative or operative along with said cooling unit of the storage chamber.

PIETRO MANISCALCO.
